UNITED STATES PATENT OFFICE

JESSE BARTON REED, OF FORT SMITH, ARKANSAS

VIOLIN BOW

Application filed April 19, 1929. Serial No. 356,491.

This invention relates to an improved musical instrument bow and it has more particular reference to a bow which is principally designed for use in performing on instruments of the string family, for instance the violin, viola, cello and double bass, although the present invention is particularly adapted for use as a violin bow.

It is matter of common knowledge that bows of this class are, in appearance, somewhat the same.

Persons skilled in this art, however, are well aware of the fact that the better types of bows are unusually expensive and vastly different from cheap bows.

From experience I have found that cheap bows which are inaccurately constructed as a rule constitute an unusual handicap to a performer.

Good bows, which call for rather exorbitant retail prices are immediately recognized by even the amateur performer when compared with the undependable cheap bow.

While not desiring to dwell upon laudatory statements, I feel called upon to make this comparison in order to enable the reader to appreciate the novelty embodied in the present bow construction.

It follows, therefore, that what I have in mind is the provision of an improved bow, the principal features of which are constructed of metal instead of wood, as is usual, thereby minimizing the expense of manufacture and reducing the retail charge, whereby to permit the humble and moderate performer to be able to obtain a bow which possesses the buoyant elastic and captivating qualities of the more expensive hand constructed bows now on the market.

Briefly stated, I have conceived of the idea of making the staff from a single length or strip of resilient steel or metal which is channel shaped in cross section and which is connected at its outer end with an aluminum tip and at its inner end with an aluminum hand grip, the remaining features of the bow being substantially the same as in the ordinary construction of bows.

In carrying the invention into effect, I have evolved and produced a simplified and

economical structure which will well fulfill the requirements of an otherwise expensive structure, and one which may be rendered unusually ornate in that it may be highly polished and burnished and otherwise adapted to better fulfill the requirements of an accessory of this class.

In the drawings:

Figure 1 is an elevational view of a complete bow constructed in accordance with the present invention.

Figure 2 is a fragmentary detail section and elevation of frog mounting and analogous details, constructed in accordance with the present invention.

Figure 3 is a transverse vertical section on the line 3—3 of Figure 2.

Figure 4 is a similar section on the line 4—4 of Figure 2.

Figure 5 is a section on the line 5—5 of Figure 1.

Referring now to the drawings by parts, it will be observed that the reference character 6 designates the stick or staff. In accordance with the present invention it is in the form of a single length of spring steel which is bowed longitudinally and tapered from the inner toward the outer end, in order that it will possess the general contour or shape of the ordinary wooden stick. This particular staff is channel shaped in cross section and the open side of the channel is toward the bottom. One end of the staff is suitably attached to the tip 7. The tip is here shown as of usual configuration, but made of aluminum. It is formed with a socket into which the adjacent end of the tab 6 extends, and a wooden plug 7^a is driven into this socket to bind the staff and to provide the necessary connection. A similar connection is provided at the opposite end of the staff where it is connected with an aluminum hand or finger grip 8. This is in the form of an elongated body of the configuration shown. It is formed at the outer end of the socket receiving the staff as shown in Figure 2 and also receiving a driven plug 9. The reference character 10 merely designates a knurled anti-slipping surface which is preferably provided. The

opposite end portion of this finger grip is recessed and bored to accommodate the usual adjusting screw 11. This screw has a turning nut or finger grip 12 at the outer end and has its inner end reduced to provide a spindle at 13 receivable in a counter-bored bearing socket as shown in Figure 2. The threaded portion of the stem is fed through an adjusting nut 14 carried by the usual frog 15.

10 The customary parallel strands of hair 16 are strained between the tip 7 and the frog 15 and bonded in place in the usual manner.

15 The gist of the invention, as before indicated is in the provision of a spring metal channel shaped longitudinally bowed staff connected at one end with an aluminum tip and connected at its opposite end with an 20 aluminum hand grip, together with the conventional hair adjusting means and frog.

It has been found that a bow of this construction may be manufactured and sold at an unusually low figure. Therefore, persons in moderate circumstances will be able 25 to acquire a dependable and efficient form of bow which will decidedly add to strength, durability and buoyant and resilient properties.

30 It is thought that by considering the description in connection with the drawings, a clear understanding of the construction, operation and features of the invention will be had. Therefore a more lengthy description 35 is regarded as unnecessary.

Minor changes in the shape, size and materials coming within the field of invention claimed may be resorted to, in actual practice, if desired.

40 I claim:

1. A musical instrument bow of the class described comprising a longitudinally bowed staff in the form of a resilient metal stick of half circular channel shaped cross section, a tip in one end of the staff, a frog adjustably mounted on the opposite end of the staff, and hair trained between the tip and frog in a conventional manner.

2. A musical instrument bow of the class described comprising a staff in the form of a longitudinally bowed and tapered resilient metal stick of half circular channel shaped cross section, an aluminum tip attached to one end of the staff, a frog adjustably mounted on the opposite end of the staff, and hair stretched between and connected with the frog and tip respectively.

3. A musical instrument bow comprising a longitudinally bowed and tapered staff in the form of a resilient metal stick of half circular channel shaped cross section, an aluminum tip mounted on one end of the staff, an aluminum hand grip having a socket receiving the adjacent end of the staff, a tapered plug driven into said socket for hold-

ing the staff in position, a frog adjustably mounted on said hand grip and hair stretched between said tip and frog.

4. A violin bow staff in the form of a longitudinally bowed and tapered body of resilient metal, said body being of half circular channel shaped cross section and decreasing gradually in cross section from its inner to its outer end.

In testimony whereof I affix my signature. 75
JESSE BARTON REED.
